ABSTRACT

A magnetic lifting element for shipping cages such as poultry coops in the form of a flat pad comprising magnetic material and having hook members extending from the bottom of the pad for engaging the edges of holes in the top of the cage. The shanks of the hook member are longer than the thickness of the cage top to permit at least approximately one-half inch vertical displacement of the pad from the top of the cage after the hook members are inserted through the holes for accommodating possible vertical misalignment between an elongated magnetic pickup boom and the tops of a row of cages to be loaded on or off a truck.

MAGNETIC LIFTING ELEMENT

BACKGROUND OF THE INVENTION

This invention relates to magnetic lifting devices and particularly to pads of magnetic material for lifting shipping cages by means of electromagnetic booms.

When shipping poultry it is customary to place about a half dozen birds in each of a number of openwork cages or coops and then to fill a long truck bed with rows of coops stacked several layers deep, with well over one hundred coops per truck. To unload the cages individually by manual labor is time-consuming and subjects the birds to possible injury by rough handling of the cages.

The unloading process has been mechanized by some shippers who fasten steel plates to the top of each cage, one plate near each end, by screwing, bolting or welding the plate directly to the cage. A boom fitted with electromagnets can then be lowered into contact with the plates on the cage, the magnets energized, and the cage lifted off the truck to any desired location.

The unloading process can be speeded still further by using an extended boom capable of picking up several cages in a horizontal row simultaneously. It is necessary that the cage tops be almost perfectly aligned in a plane, however, because the attractive force of the magnets falls rapidly as the gap between the boom and the lifting plate increases. Since such perfect alignment is rarely achieved in practice, usually one cage, or only a few at most, can be unloaded at a time.

SUMMARY OF THE INVENTION

It is an object of the present invention to provide a magnetic lifting element for shipping cages that will permit unloading and loading a horizontal row of cages extending the entire width or length of a truck bed.

It is another object of the invention to provide a magnetic lifting element for shipping cages that can be easily installed in the field.

Another object of the invention is to provide a magnetic lifting element of simple, one-piece design.

A more specific object of the invention is to provide a one-piece magnetic lifting for a shipping cage that can be permanently attached to the cage with fastening means that permit substantial vertical movement of the lifting element with respect to the cage top.

These and other objects are accomplished by a magnetic lifting element that comprises a flat pad, at least the major portion of which consists of magnetic material, at least one attachment member extending approximately perpendicularly from one face of the flat pad, and a transverse stop means located near the outer end of the attachment member. The attachment member is adapted to be inserted loosely through an opening in the top of a shipping cage, such as an openwork poultry coop, and the stop means is adapted to engage the under surface of the cage top adjacent to the edge of the hole to prevent withdrawal of the attachment member after it has been inserted through the hole.

An important feature of the invention is that the stop means is spaced from the one face of the pad by a distance substantially greater than the thickness of the cage top to allow vertical movement of the flat pad away from the upper surface of the cage before the stop member engages the under surface for accommodating possible vertical misalignment between a pickup boom and the top of the cage. The spacing of the stop means

should allow for at least about one-half inch of vertical movement and can be even more, depending on the field strength of the boom electromagnet. Since the relatively light magnetic lifting element is free to move by itself under the influence of the electromagnetic field upward into contact with the boom, a given magnet strength is effective across a much greater gap than when the entire weight of a filled cage must be lifted.

A preferred embodiment of the invention includes at least two attachment members, each member having a side that is substantially perpendicular to the one face of the flat pad, the side of one attachment member facing in an opposite direction from the side of the other attachment member, and the two sides being spaced apart to provide loose sliding contact by said sides with corresponding edges of at least one hole through the top of a shipping cage when the attachment members are inserted therethrough.

The transverse stop means preferably comprises a wedge-shaped hook portion integrally formed at the outer end of each attachment member, each hook portion having a sloping face for engaging at an angle the corresponding edge of the hole to facilitate insertion of the attachment member and a rear portion extending from the side of the attachment member for engaging the undersurface of the cage top adjacent to the edge of the hole after the attachment member has been inserted.

In one preferred form, the magnetic lifting element consists of a single iron casting. This form is particularly adapted for mounting on a molded plastic poultry shipping cage of the type that has a flat top surface approximately one-quarter inch thick pierced by rows and columns of rectangular openings to form a lattice-like grid. The plastic is sufficiently resilient to permit insertion of the integral attachment members, which are too stiff themselves to bend appreciably. At the same time the plastic is strong enough to resist pulling out of the stop portions of the attachment members after insertion.

Such a type of plastic poultry cage is disclosed in my U.S. Pat. No. 3,754,676, issued on Aug. 28, 1973. The cage of that patent also includes integral longitudinal and transverse vertical stiffening webs that divide the upper surface of the cage into rectangular wells having at least one of the rectangular openings at the bottom of each well. The flat pad of the cast iron lifting element is preferably a rectangular plate having a thickness approximately equal to the height of the webs and being sized to fit loosely within one of such wells with the top approximately flush with the tops of the stiffening webs.

Another preferred embodiment is in the form of a rectangular magnetic metal plate tightly encased in a plate holder of molded plastic enclosing the edges and bottom of the metal plate. The attachment members are integrally formed as extensions of the plate holder. Being made of plastic these attachment members may have some slight resiliency so as to bend when the hook portion is inserted into an opening in the cage top. This feature makes the plastic-enclosed steel plate type of magnetic lifting element particularly suitable for use with metal poultry cages, either of welded wire or stamped sheet metal, or even with wood cages that are too stiff to deflect when the attachment members are being inserted.

In an especially preferred design of the plastic-encased embodiment, the edges of the metal plate are bevelled outwardly from the top of the plate to the bottom to securely wedge the plate into the plate holder, although other keying elements such as ridges or ribs may be used, if desired.

The foregoing and other features of the magnetic lifting element of the present invention will be more fully described in connection with the preferred embodiments as illustrated in the accompanying drawings.

BRIEF DESCRIPTION OF THE DRAWINGS

FIG. 1 is a perspective view of a poultry shipping cage having two magnetic lifting elements mounted on the top.

FIG. 2 is a perspective view of a lifting pad embodiment prior to insertion through openings in the top of a shipping cage.

FIG. 3 is a side view in partial section of a plastic-encased alternate embodiment of a magnetic lifting pad after insertion through openings in the top of a shipping cage.

FIG. 4 is a side view of an electromagnetic pickup boom engaging magnetic lifting elements of separate cages in a horizontal row.

DESCRIPTION OF THE PREFERRED EMBODIMENTS

In reference to FIG. 1, a pair of magnetic lifting elements 10 are shown mounted on the top of a molded plastic poultry shipping cage 11. The cage is of the type disclosed in the above-mentioned U.S. Pat. No. 3,754,676 in which the top, bottom, and sides are formed as basically flat sheets pierced by columns and rows of rectangular ventilation holes and strengthened by integral longitudinal and transverse external webs. Specifically, the top of cage 11 is in the form of a flat sheet 12 pierced by rectangular openings 13 to produce a lattice-like grid pattern. Longitudinal stiffening webs 14 and transverse stiffening webs 15, formed integrally with flat sheet 12, divide the upper surface of the cage into rectangular wells each enclosing at least one of the rectangular openings.

Each magnetic lifting elements 10 is in the form of a flat rectangular pad 16 sized to fit loosely within one of the rectangular wells on the upper surface of the cage top, the thickness of the pad being approximately the same as the height of the stiffening webs so that the top of the pad is about even with the top edges of the webs.

As shown more clearly in FIG. 2, at least one attachment member, such as hook members 17, extends approximately perpendicularly from the lower surface of flat pad 16 for loose-fitting insertion through openings 13 in the bottom of the well. Each hook member includes a shank portion 18 having a face 19, a transverse stop portion 20 extending from the face near the lower end of the shank portion, and a sloping end portion 21 extending from the outer edge of the stop portion to the tip of the hook member. Depending on the number and arrangement of openings in the cage top that are spanned by the flat pad, more than one attachment member may be used to hold the pad to the top of the cage. In the illustrated embodiments, for example, a pair of oppositely facing hook members are positioned adjacent to opposite edges of the pad. The sloping end portion of each hook member engages an adjacent edge of one of the openings 13 to facilitate insertion of

the hook members through the openings. After insertion, the stop portion of each hook member engages the under surface of flat sheet 12 when the lifting element is raised, to prevent removal of the element from the cage.

As mentioned earlier, it is an important feature of the present invention that the stop portion of each hook member is spaced from the bottom face of the pad by a distance substantially greater than the thickness of the top surface of the cage, preferably at least twice that thickness, to allow vertical movement of the flat pad away from the upper surface of sheet 12 before the stop portion engages the under surface of the sheet for accommodating possible vertical misalignment between an electromagnetic pickup boom and the top of the cage.

For example, the thickness of sheet 12 may be about one-quarter inch for a molded plastic cage of the type illustrated in the drawing, and the spacing of the stop portion of each hook member from the bottom of the pad may range from about one-half inch to one inch or more, being preferably about three-quarters of an inch for the application illustrated. The spacing chosen for any particular size of lifting element will depend primarily on the maximum vertical distance across which the electromagnetic boom can attract the element.

The lifting element embodiment of FIG. 2 consists of a single piece of magnetic material such as steel or iron. A particularly inexpensive method of manufacture is to make the element as an iron casting. The hook elements of such a casting will be essentially inflexible, but there is sufficient resilience in the plastic material of the cage top to permit insertion of the hook members past the adjacent edges of the openings without causing permanent deformation.

FIG. 3 shows an alternative embodiment of the magnetic lifting element of the invention that may be used with shipping cages of relatively resilient plastic, such as high impact plastic, but that is even more suitable for cages of metal, wood, or other material that cannot be resiliently deformed to the extent necessary to allow insertion of the hook member. In this alternative embodiment the lifting element comprises a rectangular steel plate 22 that is tightly encased in a molded plastic plate holder 23 in the form of a flat, open-top box surrounding the edges and bottom of the plate. The plate holder has integrally molded hook members 17' similar to the hook members of the all metal embodiment of FIG. 2.

To insure a tight fit of the plate in the plate holder the edges of the plate are bevelled outwardly from top to bottom to wedge the plate into the plate holder. Although this is a particularly simple arrangement, inexpensive to fabricate, other forms for accomplishing the same purpose can be used, such as ribs, grooves, or steps arranged to lock the plate into the plate holder.

The plate holder is preferably molded from thermoplastic material having some inherent resiliency so that the shanks 18' of the hook members will act as leaf springs to yieldably permit the sloping end portions 21' to be inserted past the adjacent edges of openings 13, the shanks then straightening so that surfaces 20' will engage the under side of the cage top when the lifting elements are raised by a magnetic boom.

FIG. 4 illustrates the operation of the magnetic lifting elements of the present invention and particularly shows the advantage resulting from allowing relative

vertical movement of each element away from the cage top before the stop means engages the under surface of the top. In FIG. 4 an elongated horizontal electromagnetic boom 24 is positioned over a row of shipping cages 11 equipped with magnetic lifting elements 10, two of which are shown.

When a row of cages are placed on a truck, the tops of the cages are often not completely aligned in one plane due to irregularities of the truck bed surfaces or small differences in the height of the cages. Consequently, the boom may contact only one or two of the magnetic plates, and there will be an air gap of as much as one-half inch or more between the bottom of the boom and the top surfaces of the lowest plates in the row.

If the plates are rigidly fastened to the cages, the boom magnets must be powerful enough to attract the plates against gravitational force acting on the entire filled cage. By spacing stop surfaces 20 from the bottom of flat pads 16 by a distance substantially greater than the thickness of sheet 12, the pads move freely upward into contact with the lower surface of boom 24 when current is turned on to the electromagnets before surfaces 20 engage the under side of sheet 12. Thus, vertical misalignment between cages, as shown in the drawing, is accommodated without requiring excessively powerful boom magnets. The limited free vertical travel of the lifting elements also prevents a sudden shock to the poultry or other contents of the shipping cages when the electromagnet current is first turned on and the lifting elements snap into contact with the boom. After the plates have made contact, the magnetic attraction force is fully strong enough to lift the full cages with the boom for placement at any desired location.

As a specific example for use with poultry shipping coops of the type described, two magnetic lifting elements have been used with one cage, each element having a flat steel pad approximately 3 inches by 5 inches by $\frac{3}{4}$ inch in size and having a hook member shank length sufficient to provide approximately $\frac{1}{2}$ - $\frac{3}{4}$ inch of free vertical movement of the pad with respect to the cage top. Other sizes and weights of shipping cages may require different dimensions of lifting elements, as may be determined easily by experiment.

I claim:

1. A magnetic lifting element for mounting on top of a shipping cage to permit lifting the cage by means of an electromagnetic pickup boom, the cage having at least one opening through the top thereof, wherein the lifting element comprises:

a flat pad, the major portion of which is composed of magnetic material;
at least one attachment member extending approximately perpendicularly from one face of the flat pad for loosefitting insertion through the opening in the top of the cage; and

a transverse stop means located near the outer end of the attachment member for engaging the under surface of the cage top to prevent withdrawal of the attachment member after it has been inserted through said opening, the transverse stop means being spaced from the one face of the pad by a distance substantially greater than the thickness of the cage top to allow vertical movement of the flat pad away from the upper surface of the cage before the stop member engages the under surface for accom-

modating possible vertical misalignment between the pickup boom and the top of the cage.

2. The magnetic lifting element of claim 1 including at least two attachment members, each attachment member having a side that is substantially perpendicular to the one face of the flat pad, the side of one attachment member facing in an opposite direction from the side of the other attachment member, and the two sides being spaced apart to provide loose sliding contact by said sides with corresponding edges of the at least one opening through the top of the cage when the attachment members are inserted therethrough, and the transverse stop means comprises hook portions integrally formed at the outer end of each attachment member, each hook portion having a sloping face for engaging at an angle the corresponding edge of the at least one opening in the top of the cage to facilitate insertion of the attachment members therethrough and a rear portion extending from the perpendicular side to engage the under surface of the cage top adjacent to the corresponding edge of the opening after the pad is mounted on the top of the cage.

3. The magnetic lifting element of claim 1 wherein the transverse stop means is spaced from the one face of the pad by a distance sufficient to allow vertical movement of at least one-half inch of the flat pad away from the upper surface of the cage.

4. The magnetic lifting element of claim 1 wherein the element is made of cast iron.

5. The magnetic lifting element of claim 1 wherein the flat pad comprises:

a rectangular magnetic metal plate and
a plate holder in the form of a flat, open-top box of molded plastic material tightly encasing the edges and bottom of the metal plate.

6. The magnetic lifting element of claim 5 wherein the edges of the magnetic metal plate are bevelled outwardly from the top of the plate to the bottom of the plate to wedge the plate into the plastic plate holder.

7. A magnetic lifting element particularly adapted for mounting on a molded plastic poultry shipping cage of the type having a top surface pierced by rows and columns of openings to form a lattice-like grid and reinforced by integral longitudinal and transverse vertical webs that divide the upper surface of the cage top into rectangular wells each enclosing at least one of the openings, the lifting element comprising:

a flat rectangular pad comprising magnetic material and sized to fit loosely within one of the rectangular wells on the upper surface of the cage and a plurality of hook members extending from the bottom face of the pad adjacent to opposite edges thereof, each hook member including a shank portion having a face substantially perpendicular to the bottom face of the pad for making loose sliding contact with an adjacent edge of the at least one opening enclosed by the well, a transverse stop portion extending from the face of the shank near the lower end of the hook member for engaging the under surface of the cage top after the hook member has been inserted through the hole, the stop member being spaced from the bottom face of the pad by at least twice the thickness of the top surface of the cage to allow vertical movement of the pad out of the well before the stop member engages the under surface of the cage top, and a sloping end portion extending from the outer edge of the stop portion toward the tip of the hook member for engaging at an angle the adjacent edge of the opening to facilitate insertion of the hook member therethrough.

8. The lifting element of claim 7 consisting of a single piece of magnetic metal.
